United States Patent Office

Des. 185,753
Patented July 28, 1959

185,753

GOLFING VEHICLE OR SIMILAR ARTICLE

William A. Jensen, Addison, Ill.

Application January 6, 1959, Serial No. 54,049

Term of patent 14 years

(Cl. D14—3)

Fig. 1 is a perspective view of a golfing vehicle or similar article, showing my new design;

Fig. 2 is a top plan view;

Fig. 3 is a side elevational view;

Fig. 4 is a rear elevational view; and

Fig. 5 is a front elevational view.

I claim:

The ornamental design for a golfing vehicle or similar article, as shown.
